UNITED STATES PATENT OFFICE.

HUGH A. FRASER, OF SARNIA, CANADA.

WATER-HEATING FURNACE.

SPECIFICATION forming part of Letters Patent No. 708,217, dated September 2, 1902.

Application filed April 14, 1902. Serial No. 102,797. (No model.)

To all whom it may concern:

Be it known that I, HUGH A. FRASER, a citizen of the United States, residing at Sarnia, in the Province of Ontario and Dominion of Canada, have invented certain new and useful Improvements in Water-Heating Furnaces; and I do hereby declare the following to be a full, clear, and exact description of the invention, such as will enable others skilled in the art to 5 which it appertains to make and use the same.

This invention is a water-heating and steam-generating furnace especially adapted for warming buildings and for similar service.

The improvements consist in the novel construction of the furnace-shell, the arrangement of the water-heating surfaces, and in the means for deflecting and guiding the hot furnace-gases, so as to bring them intimately into contact with the entire area of both the 15 inner and outer surfaces of the water-spaces and with the main conducting-pipe.

The invention is illustrated in the accompanying drawings, in which—

Figure 1 is a side elevation of the furnace 25 with the outer jacket or casing removed, the upper part being broken away to show a part-sectional view on the line *x* *x* of Fig. 3. Fig. 2 is a top plan view of the furnace with its outer casing removed. Fig. 3 is a front elevation of the furnace, the upper part being broken away to show a transverse section on the line *y* *y* of Fig. 1.

As is clearly shown in the drawings, the furnace consists in a hollow water-containing shell 1, its cross-sectional shape being substantially that of an inverted letter **U**. The shell has a hollow water-containing end 2, which forms the back for the combustion-chamber 3. An opening 4 through the shell 1 near its rear 30 end permits the gases to escape into the space between the shell 1 and an outer jacket or casing 5, which surrounds the shell 1 and corresponds with it in general shape. The main pipe 6, through which the steam or hot water is delivered for distribution through the building, communicates with the water-space of the shell 1 near its front end and extends rearwardly above the opening 4, so as to receive the impact of the hot gases. A 45 pair of deflecting-plates 7 extend horizontally around the lower part of the shell 1 and its back 2 and form a horizontal deflecting-plate

or partition spanning the space between the hollow shell 1 and the outer casting 5. The deflecting-plates are discontinued near the 55 front of the furnace, leaving openings 8 at each side through which the products of combustion pass downwardly on their way to the smoke-pipe 9, as shown by the arrows. A rocking grate 10 supports the fuel-bed in the 60 combustion-chamber 3.

The operation of the furnace is as follows: Hot gases from the fire in the combustion-chamber 3 pass upwardly through the opening 4 in the water-containing shell 1 after 65 coming in contact with the heating-surface of the interior of the shell. Above the opening 4 they impinge against and surround the distributing-pipe 6 and flow between the shell 1 and the outer casing 5 downwardly 70 and rearwardly, sweeping over the outer heating-surfaces of the top and side of the shell 1. The gases then pass down through the openings 8 and thence back under the partitions 7, around the return-pipes 11, and 75 out through the smoke-pipe 9 into the chimney. To thoroughly heat the outer surface of the water-back 2, I provide openings 12 through the partition 7 in proximity to the smoke-pipe outlet. A flow of hot gases from 80 the openings 4 is induced by the chimney-draft down the back 2 and into the pipe 9 through the openings 12, thoroughly heating the water in the back 2. In practice I prefer to cast the shell 1 in a single piece, thereby 85 not only reducing the cost of manufacturing but also doing away with joints, that might in practice develop leaks.

By the means above described I have produced a heating-furnace that is simple in 90 construction, having its entire water-containing space inclosed by a single casting and so disposed with reference to the fire-bed that the gases of combustion traverse the entire area of the water-space both inside and out and also flow around the main distributing-pipe. I thus secure a large area of highly-efficient heating-surface in a furnace requiring a relatively small amount of metal for its construction.

What I claim as my invention, and desire to secure by Letters Patent, is—

1. A water-heating furnace comprising in combination an inner water-containing shell

of inverted-**U** section; an outer casing inclosing said shell; an opening through the top of the water-containing shell near its rear end, connecting the combustion-chamber with the space between the shell and the casing; a horizontal deflecting-plate extending around the lower part of the shell and connecting the shell and casing; openings near the front ends of said deflecting-plate; **10** a smoke-pipe communicating with the interior of the casing below said deflecting-plate; and openings in the deflecting-plate in proximity to the smoke-pipe, for the purposes set forth.

15 2. In a furnace the combination of a combustion-chamber inclosed by an inverted water-containing shell of substantially **U**-shaped section having a water-containing end, said shell and end being formed in one

piece; an opening for the passage of hot **20** gases from the combustion-chamber through the upper part of said shell near its rear end; a distributing-pipe extending above said opening; an outer casing inclosing the distributing-pipe and shell; a horizontal **25** deflecting-partition near the lower part of said shell, connecting the shell and casing and extending along the sides and back of the shell; and openings for the passage of hot gases near the front ends of said partition; **30** all arranged and operating for the purposes set forth.

In testimony whereof I affix my signature in presence of two witnesses.

HUGH A. FRASER.
